US00D683461S

(12) **United States Design Patent**
Mürner et al.

(10) **Patent No.:** US D683,461 S
(45) **Date of Patent:** ** May 28, 2013

(54) **HINGE COUPLING**

(75) Inventors: **Beat Mürner**, Reichenbach (CH); **Axel Bernhard Cremer**, Lommiswil (CH); **Adam Busch**, Olten (CH); **Robert Dominik**, Lausanne (CH)

(73) Assignee: **Stryker Trauma SA** (CH)

(**) Term: **14 Years**

(21) Appl. No.: **29/394,179**

(22) Filed: **Jun. 14, 2011**

(30) **Foreign Application Priority Data**

Dec. 14, 2010 (WO) 577 932 301

(51) **LOC (9) Cl.** 24-03

(52) **U.S. Cl.**

USPC **D24/171**

(57) **CLAIM**

The ornamental design for the hinge coupling, as shown and described.

DESCRIPTION

FIG. 1 is a perspective view of a hinge coupling, in accordance with one embodiment of the present invention.

FIG. 2 is a front view of the hinge coupling shown in FIG. 1.

FIG. 3 is a left side view of the hinge coupling shown in FIG. 1.

FIG. 4 is a back view of the hinge coupling shown in FIG. 1.

FIG. 5 is a right side view of the hinge coupling shown in FIG. 1.

FIG. 6 is a top view of the hinge coupling shown in FIG. 1; and,

FIG. 7 is a bottom view of the hinge coupling shown in FIG. 1.

1 Claim, 6 Drawing Sheets
